UNITED STATES PATENT OFFICE.

FRANK H. MINGAY, OF BERFIELD, BRIDGE OF WEIR, SCOTLAND.

GOLF-BALL.

No. 889,709.

Specification of Letters Patent.

Patented June 2, 1908.

Application filed April 7, 1906. Serial No. 310,517.

To all whom it may concern:

Be it known that I, FRANK HEDLEY MINGAY, of Berfield, Bridge of Weir, in the county of Renfrewshire, Scotland, bank-teller, a subject of the King of Great Britain, have invented certain new and useful Improvements in Golf-Balls, of which the following is a specification.

This invention relates to balls for use in the game of golf in which a ball having a core or heart is used, said core having a covering consisting of a strip or strips of rubber or other suitable substance wound on its exterior surface and the whole being inclosed in an outer casing of gutta percha or the like.

The invention has for its object to improve the construction of the cores of such balls.

In carrying out my invention I employ an incompressible liquid such as water or other liquid or semi-liquid, contained in a suitable receptacle or shell made of elastic material, preferably vulcanized india rubber or the like, and also preferably of spherical or nearly spherical shape and with or without an orifice for the admission of the liquid. The liquid is forced or inserted in the receptacle by means of a syringe, pump, or other suitable means and when the receptacle is filled the nozzle of the syringe, pump or instrument used for filling is withdrawn and the orifice through which the liquid has been inserted is closed and sealed in any suitable manner. The usual rubber or other thread or tape is then wound in the customary manner on the outer surface of the receptacle or shell, the substance contained in which, owing to its fluid nature, readily assumes, during the winding process, the spherical shape. When the receptacle has no orifice in it for the admission of the liquid then a hole is pierced in it, either by means of the sharp nozzle of the filling instrument or by means of a needle or piercer.

Any convenient incompressible liquid, such as water, treacle, glycerin, or the like, may be used to form the core or fill the receptacle or shell of the core though, in practice, I have found that water gives very satisfactory results.

On the drawing annexed:—Figure 1 shows

in section a golf ball as constructed under my invention. Fig. 2 is a view of the elastic receptacle for the liquid, but unfilled. Fig. 3 is a view of the same expanded and filled with liquid.

The receptacle preferably consists of a small india rubber bag *a* of spherical or other suitable shape and which may or may not be provided with a tubular part *b* for the admission of the liquid. The fluid may be forced into the receptacle *a* by means of a syringe, pump, or the like, the nozzle of which is inserted in the tubular part *b*, when the receptacle is made with such a part, and, when the receptacle is filled and expanded (see Fig. 3) the nozzle is withdrawn, and the tubular part or orifice through which the liquid has been inserted closed either by tying a piece of cord, rubber, or other thread or the like *c* tightly round its exterior or by other suitable means. The usual rubber or other thread or tape *f* is tightly wound, in the customary manner, round about the outer surface of the receptacle and on the cover or casing formed by this rubber thread or tape the usual outer cover or shell *e* may be formed or fitted in any well known and convenient manner. When the rubber bag *a* is expanded by the liquid it, of course, by its contractile action, presses on the fluid and thereby insures, practically speaking, a solid although mobile core.

Having now fully described my invention, what I claim and desire to secure by Letters Patent is:

1. A playing ball having an expanded core of thin elastic material, an incompressible liquid filling said expanded core and a layer of elastic material under tension surrounding said core.

2. A playing ball having an expanded core of thin elastic material, a wrapping of elastic tape or thread under tension over said core, and an incompressible liquid filling said expanded core.

In testimony whereof I affix my signature in presence of two witnesses.

F. H. MINGAY.
